UNITED STATES PATENT OFFICE.

CHARLES A. FOLMER, OF BERNHARTS, PENNSYLVANIA.

DESIGN FOR AN AUTOMOBILE-TOP.

55,855.

Specification for Design.

Patented July 20, 1920.

Application filed June 1, 1920. Serial No. 385,841. Term of patent 7 years.

To all whom it may concern:

Be it known that I, CHARLES A. FOLMER, a citizen of the United States, residing at Bernharts, in the county of Berks and State of Pennsylvania, have invented a new, original, and ornamental Design for an Automobile-Top, of which the following is a specification, reference being had to the accompanying drawing, forming a part thereof.

In the drawing:

The figure represents a side elevational view of my new design for an automobile top.

I claim:

The ornamental design for an automobile top, as shown.

CHARLES A. FOLMER. [L. S.]
